UNITED STATES PATENT OFFICE.

EDWARD C. HOCK, OF BUFFALO, NEW YORK.

SMOKE-CONSUMING ATTACHMENT FOR FURNACES.

1,285,178.

Specification of Letters Patent. Patented Nov. 19, 1918.

Application filed March 13, 1917. Serial No. 154,499.

To all whom it may concern:

Be it known that I, EDWARD CHARLES HOCK, a citizen of the United States of America, residing at Buffalo, in the county 5 of Erie and State of New York, have invented certain new and useful Improvements in Smoke-Consuming Attachments for Furnaces, whereof the following is a specification.

10 This invention relates to a simple device especially applicable to furnaces for hot water heating systems, boiler furnaces, sectional steam generators and the like, which can be readily applied to structures already 15 in use and which will deliver heated air into the fire chamber in series of jets along opposite sides thereof over the mass of burning fuel therein in such manner as to cause it to commingle with the unconsumed products 20 of combustion throughout the chamber, supplying oxygen to said products and inducing smokeless combustion thereof.

Figure 1 of the accompanying drawings represents a perspective view of a fractional 25 portion of one side of a hot water furnace or sectional steam generator, showing applied thereto a smoke consuming attachment embodying one form of this invention, the delivery jets being directed downward.

30 Fig. 2 represents the same furnace part provided with another embodiment of this invention.

Fig. 3 represents a plan view of a furnace with parts broken out, showing the smoke 35 consuming attachment applied in the same manner as in Fig. 1.

Fig. 4 represents a perspective view of one of these devices detached from the furnace, parts being broken out.

40 Fig. 5 represents an end elevation of a delivery nozzle of this smoke consuming attachment.

Fig. 6 represents a longitudinal section thereof on line 6—6 of Fig. 5.

45 The same reference numbers indicate corresponding parts in the different figures.

This invention is illustrated in its application to a fire chamber having water legs on its opposite sides and three separate 50 series of transverse water tubes connected with said water legs, one series being disposed above another and the tubes of each series being disposed apart from one another.

55 In the preferred form of embodiment shown in Figs. 1, 3 and 4, the smoke con-

suming attachment comprises longitudinal air supply pipes 10 resting at opposite sides of the furnace respectively against the water legs on the lower series of arched 60 transverse tubes at the points of junction thereof with said water legs. Branch pipes 20 are connected at determinate intervals with said air supply pipes and extend downward therefrom between said arched tubes 65 and terminate within the fire chamber below said pipes. These branches are preferably slightly curved upward at their inner ends.

The inner ends of these lateral branches are provided with air distributive nozzles of 70 any suitable form. In the form shown the outer end of each branch pipe 20 is provided with an internal screwthread 21 and with a multiplicity of lateral orifices 22 near the outer end of the branch and with another series of lateral orifices 23 disposed around the branch at a greater distance 75 from the end thereof. An example of a nozzle 20' in duplex form is shown in Fig. 1. This duplex nozzle 20' may be used independently or in connection with the single nozzles 20. This duplex nozzle comprises two laterally curved branches and when used between the single nozzles 20 it delivers the air in diverging streams which commingle 80 with the streams of adjacent nozzles and tends to spread the distributive air over the fire. A cylindrical plug 25 is provided with external screwthreads 26 fitting the screwthreads of the branch tube. This plug 85 is provided on its periphery with a series of longitudinal channels 27 which taper from the inner face of the plug to the outer face thereof and form delivery orifices 28 at the outer face thereof. These tapering 90 channels are preferably V-shaped in cross section. The plug 25 may be adjusted inward or outward to increase or diminish the direct delivery orifices 28 as well as the lateral delivery orifices 22 and 23. In such 95 adjustment the triangular V-shaped channels are exposed at the peripheries whereby a slight movement of the plug will effect substantial changes in the delivery orifices. For instance an outward turning of the 100 plug 25 from the position shown in Fig. 6, where it is flush with the end of the nozzle 20, will enlarge the orifices of said channels, which flare inward, such enlargement being proportional to the distance said plug is 105 turned outward. Such outward turning also brings the deeper portions of said chan-

110

nels opposite the lateral orifices 22 and 23 and enables a larger volume of air to pass out through said lateral orifices.

In the form of embodiment shown in Fig. 2 the air supply pipes 10 are disposed on opposite sides of the combustion chamber of the furnace below the lowermost series of arched transverse tubes but in contact therewith at their points of junction with 10 said water legs and the branch pipes 20 thereof disposed at regular distances apart opposite the spaces between said arched tubes are slightly inclined upward, and the plugs 25 thereof are of the same construction as those of the branch pipes 20. The air supply pipes 10 in both forms of embodiment are disposed at the lowermost series of transverse water tubes and the branch pipes 20 or 40 are subjected to the action 20 of the currents of hot gases passing through the spaces between the water tubes and are in position to deliver the heated air through the nozzles to directly intermingle with said gases as soon as they leave the coal.

25 The air supply pipes 10 may be provided with an injector 11 as shown in Fig. 3 of a construction like that illustrated in my Patent No. 1,106,709, dated August 11, 1914.

In the use of this device, two tubes 10 are 30 disposed within the combustion chamber on opposite sides of the walls thereof and the lateral branches 20 or 40 thereof project inward to points over the mass of burning coal, and deliver jets of heated air into said chamber along the whole length thereof. The air thus delivered is thoroughly mixed 35 and commingled with the products of combustion and supplies oxygen thereto, whereby said products are ignited and consumed.

40 The air distributors constituting this smoke consuming device may be hung over the arched water tubes and project downward between them or be supported along the vertical tubes on opposite sides of the 45 chamber.

I claim as my invention:

1. The combination with a fire chamber 50 provided with arched water tubes disposed apart from one another and having water legs on opposite sides of said chamber of a smoke consuming attachment comprising longitudinal air supply tubes resting on said arched tubes at opposite sides of said chamber, branch tubes at determinate intervals connected with said air supply tubes and extending 55 downward between said arched tubes and provided with distributive nozzles projected into said chamber below said arched tubes.

60 2. The combination with a fire chamber provided with arched water tubes disposed apart from one another and having water legs on opposite sides of said chamber of a smoke consuming attachment comprising longitudinal air supply tubes resting on said 65

arched tubes at opposite sides of said chamber, branch tubes at determinate intervals connected with said air supply tubes and extending downward between said arched tubes, and distributive nozzles disposed on 70 said branch tubes and projected into said chamber, said nozzles having direct and lateral delivery orifices.

3. The combination with a fire chamber 75 provided with arched water tubes disposed apart from one another and having water legs on opposite sides of said chamber of a smoke consuming attachment comprising longitudinal air supply tubes resting on said arched tubes at opposite sides of said chamber, branch tubes at determinate intervals connected with said air supply tubes and extending downward between said arched tubes, and distributive nozzles disposed on 80 said branch tubes and projected into said chamber, said nozzles having direct and lateral delivery orifices and provided with 85 means for varying said orifices.

4. The combination with a fire chamber 90 having arched water tubes disposed apart from one another and having water legs on opposite sides of said chamber of a smoke consuming attachment comprising longitudinal air supply tubes resting on said arched tubes at opposite sides of said chamber, and inwardly projecting branch tubes 95 at determinate intervals connected with said air supply tubes, extending downward between said arched tubes into said chamber, curved upward at their outer ends and provided with distributive nozzles projected 100 into said chamber below said arched tubes.

5. The combination with a fire chamber 105 having water legs on its opposite sides and provided with several series of transverse water tubes connected with said water legs, one series being disposed above another and the tubes of each series being disposed apart from one another, of longitudinal air supply pipes disposed on opposite sides of said 110 chamber in contact with the water tubes of the lowermost series of arched water tubes, branch pipes connected with said air supply pipes at determinate intervals corresponding to the spaces between said last named water 115 tubes in positions to be impinged by the currents of hot gases which pass between said tubes, and distributive nozzles disposed on said branch tubes and projected into said chamber directly over the fuel.

6. The combination with a fire chamber 120 having water legs on its opposite sides and provided with several series of transverse water tubes connected with said water legs, one series being disposed above another and the tubes of each series being disposed apart from one another, of longitudinal air supply pipes disposed on opposite sides of said chamber in contact with the water tubes of the lowermost series of arched water tubes, 125 130

branch pipes connected with said air supply pipes at determinate intervals corresponding to the spaces between said last named water tubes in positions to be impinged by the currents of hot gases which pass between said tubes, and distributive nozzles disposed on said branch tubes and projected into said chamber directly over the fuel, comprising a

plurality of single nozzles and an intermediate duplex nozzle having laterally curved 10 branches.
